William W. Redfield, INVENTOR

UNITED STATES PATENT OFFICE.

WILLIAM W. REDFIELD, OF MINNEAPOLIS, MINNESOTA.

DRAFTSMAN'S INK-MIXER.

SPECIFICATION forming part of Letters Patent No. 313,239, dated March 3, 1885.

Application filed May 12, 1884. (No model.)

To all whom it may concern.

Be it known that I, WILLIAM WALLACE REDFIELD, a citizen of the United States, residing at Minneapolis, in the county of Hennepin and State of Minnesota, have invented 5 certain new and useful Improvements in Draftsman's Ink-Mixers, of which the following is a specification, reference being had therein to the accompanying drawings.

10 The object of my invention is to enable draftsmen and others that use india-ink largely to mix the same ready for use, in a much shorter time and more convenient manner than usual. I would here remark that the ordinary practice 15 is to take a saucer or ink-stone or ink-slab, and after placing water therein to rub the cake of india-ink back and forth in said water until the ink is black enough and sufficient in quantity. This operation, as draftsmen well know, 20 consumes considerable time, and withal has to be repeated from time to time. The draftsman must suspend his real work for the purpose of grinding up his ink. In my invention I propose, if desired, to do away, if not entirely, 25 to a considerable extent with these evils, and to fully elucidate the same I will now describe at length my improved draftsman's ink-mixer, for the use of draftsmen and others.

In the drawings, Figure 1 represents a plan 30 view, partly in section; Fig. 2, a side elevation; Fig. 3, a side sectional elevation, and Fig. 4 a section on line *x y* in Fig. 2.

The same letters of reference are generally applicable to all the figures.

35 B is a block of wood forming a foundation. The top surface of same has a relieved boss turned on the same to fit into a correspondingly-shaped recess in the under side of an ordinary ink-cup, K, of Wedgewood ware. A rectangular pin or key prevents said cup K from revolving.

A is a casting, formed either of brass, cast-steel, or cast or malleable iron, forming, essentially, a frame-work. This frame A is secured to the foundation or base piece B by means of four screws, P P P P. A shaft, H, formed best and most economically perhaps, of cast-steel, is turned to fit nicely into a hole drilled vertically in the frame A, as the drawings show, in the hub *a* on said frame A. This shaft-hole is drilled upward to within a proper distance of the top. The remainder of the hub

a is tapped to allow a thumb-screw, D, to work therein, said thumb-screw being of a slightly smaller diameter than the shaft H.

55

From the drawings it will be seen that the shaft H extends only part way up into the hole in hub *a*. Above the shaft H is fitted into a hole in hub *a* a short cylinder, G. Above this short cylinder G is a spiral open spring, F, of moderate stiffness. Above this spring F is another short cylinder, E, against which the thumb-screw D bears on being screwed down. The shaft H has a key seat or spline, as at *h*, Figs. 2 and 4, extending the whole 60 length of cylindrical part of same. On this shaft H, and giving revolution to it, is a bevel gear-wheel, C. This bevel gear-wheel C is keyed on so that the key may be tight in the wheel C, but at the same time allow a free vertical movement downward of said shaft H through said wheel C, and along the key of said wheel C, that said key-seat *h*, Figs. 2 and 4, will engage over. To hold the bevel gear-wheel C steadily at its proper height, an interruption occurs in the hub *a* in the frame A sufficient to prevent any undesired vertical 70 movement of said bevel gear-wheel C. The lower end of the shaft H is formed of a shape shown on the drawings. A slot or recess suitable to receive the end of a stick of india-ink, I, is made at this end of the shaft H, and a thumb-screw, J, holds the cake of ink firmly 75 in the socket in the shaft H. The lower end of the india-ink rests in the ink-cup K. Motion is communicated to shaft H by the bevel-wheel C meshing into the bevel-wheel C on said shaft H. The crank shape of the lower end of said shaft makes the stick of india-ink I travel in a circular path against the bottom 80 and inside of the cup K. Pressure of the ink against said cup K is obtained by means of the shaft being free to move downward and the action of the spring F against the top of said shaft, and when the spring may happen to lose 85 some of its elasticity a few revolutions of the thumb-screw D again brings pressure on the ink, and said pressure may be increased or decreased at pleasure by turning the thumb-screw D one way or the other. The short cylinders E and G are for the purpose of protecting 90 the spring F against the revolutions of the shaft H, and also to give a bearing for the pressure exerted on screwing down the thumb-

screw D. The bevel-wheel C' is keyed tight to the shaft L, revolving in another hub on the frame A, and to the outer or other end of said shaft L is attached a crank, M, with its handle N, by which motion may be given to the entire working or moving parts. A small washer is desirable to place on said shaft L between the crank M and the end of the hub on the frame A in which said shaft L revolves.

10 In lieu of the crank M, a spur-gear connected with a clock-work movement may be used to give motion to the apparatus. In this way the time saved will be more of course than when driven by hand.

15 Another feature which is necessary for the perfect usefulness of the apparatus is a small can, m, of tin or other suitable material, attached to the frame A or the block B, and a pipe with a stop-cock, k, thereon, so that water

20 may be delivered at pleasure into the cup K.

Fig. 3 of the drawings shows a small hole and pipe, n, connecting with the same and a stop-cock, o, on the same. This is for the purpose of drawing off the liquid india-ink into

25 bottles, as some draftsmen prefer to use the india-ink in that shape.

Having now fully described my invention,

I desire to claim, and secure by Letters Patent, as follows:

1. In a draftsman's ink-mixer, the combination of the frame A, the screws P P, and the base-piece B, said base-piece having a relieved boss on top of same for the purpose of receiving an ink-cup, K, thereon, and all arranged substantially as and for the purposes hereinbefore set forth. 30

2. In a draftsman's ink-mixer, the combination of the frame A with the shaft H, having its slot h and bearing the bevel gear-wheel C, the pieces E and G, the spring F, the set-screw D, the crank-shaft L, bearing the bevel gear-wheel C', and the set-screw J, all substantially as and for the purposes hereinbefore set forth. 40

3. In a draftsman's ink-mixer, the shaft H, 45 having its slot h and a recess at end for retaining a piece of india-ink, I, substantially as described.

In testimony whereof I do affix my signature in presence of two witnesses.

WM. W. REDFIELD.
